Bert J. Lowres, East Orange, N. J., assignor to
Lowres Optical Mfg. Co., Newark, N. J., a cor-
poration of New Jersey

Application December 21, 1949, Serial No. 6,759

Term of patent 7 years

(Cl. D57—1)

To all whom it may concern:

Be it known that I, Bert J. Lowres, a citizen
of the United States, residing at East Orange, in
the county of Essex and State of New Jersey, have
invented a new, original, and ornamental Design
for Visored Sun Glasses, of which the following is
a specification, reference being had to the ac-
companying drawings, forming a part thereof.

In the drawings:

Fig. 1 is a front elevational view;
Fig. 2 is a top plan view; and
Fig. 3 is a side elevational view of visored sun
glasses embodying my new design.

I claim:

The ornamental design for visored sun glasses,
as shown.

BERT J. LOWRES.
